MOLDED FOAM POLYSTYRENE
CONSTRUCTION KIT

James O. Kuhn, Cincinnati, Ohio, assignor to Kenner Products Company, Cincinnati, Ohio, a corporation of Delaware

Filed Dec. 23, 1964, Ser. No. 420,609
4 Claims. (Cl. 280—79.2)

This invention is directed to a toy construction kit by which a child can fabricate a number of different types of toys that are sufficiently large to permit the child to get into them or onto them.

The primary objective has been to provide a kit of the type set forth, the major components of which are sufficiently light in weight to be easily lifted and handled by a child, even though they are comparatively large. Toward this end, the major components of the kit are molded of foamed polystyrene which has been found to be surprisingly strong as used in the kit and so light that even a three-year-old has no difficulty in handling the largest components of the kit.

The key element of the kit is a rectangular base unit having two wooden dowel members molded therein that give it remarkable strength. As an example, it has been found that a grown man may stand at the center of the base unit while it is supported at its two ends only without breakage. This base unit is adapted to receive the other components of the kit in various ways to make up such different toys as a military tank, a doll's cradle that rocks, a wheeled coaster, a pull cart, a toy love seat, a table and others, the number being limited only by the imagination of the child using the kit.

Other objectives of the invention will be readily apparent from the following detailed description of the drawings, in which:

FIGURE 1 is a perspective view of a toy military tank made up of components of the kit of this invention.

FIGURE 2 is a perspective view showing components of the kit made up into a toy love seat that is adapted to rock.

FIGURE 3 is a perspective view showing parts of the kit made up into a toy cradle that is adapted to rock.

FIGURE 4 shows two of the components of the kit made up to form an "easy chair."

FIGURE 5 is a perspective view, part of which is broken away, showing the base unit of the invention.

FIGURE 6 is a perspective view showing a combined rocker and axle journal.

FIGURE 7 is a perspective view showing a dowel that serves as an axle.

FIGURE 8 is a perspective view showing a preferred form of wheel that is part of the kit.

FIGURE 9 is a perspective view illustrating the bottom of one of the seat units.

FIGURE 10 is an exploded view in perspective showing the components of the kit being assembled to form a wheeled vehicle.

FIGURE 11 is an exploded perspective view showing the parts of the kit while being assembled to form the toy military tank of FIGURE 1.

FIGURE 12 is an exploded perspective view showing the components of the kit being assembled to form the "easy chair" of FIGURE 4.

FIGURE 13 is a side elevational view, shown partly in section, of a toy cannon of the type that appears in FIGURE 1.

FIGURE 14 is a fragmentary cross-sectional view taken on a line 14—14 of FIGURE 13.

In the following detailed description of the drawings, the dimensions are given by way of illustration only.

2

Specific dimensions are not intended to be considered critical, although as will be seen, certain dimensional relationships are critical, for example, the size of one part with respect to a second part.

Referring now to FIGURE 5, this figure shows a rectangular base unit designated 10. As shown, this base unit, in the preferred embodiment, is roughly two and one-half times as long as it is wide. The base unit is molded of foamed polystyrene and it has two wooden dowels 11—11 molded into it that extend parallel to the longitudinal center line of the unit, being at the two sides of this center line. As shown, the dowel rods are square in cross section. Preferably, the dowel rods 11 are embedded completely within the base unit, stopping short of the two ends thereof.

Base unit 10 has a total of eight double holes 12 in it that are disposed in a pattern in which two sets of four each are in each of the two endwise portions of the unit. Each double hole 12 consists of two individual holes 13—13 that are formed such that they taper coming in from the opposite faces of the unit so that the smallest diameter occurs at a point 14 midway between said two faces. The two holes of each double hole have their centers spaced such that the distance between the centers is approximately equal to three-quarters of the diameter of an individual hole. On FIGURE 5, this distance between centers is designated y . Considering the four double holes that are in the left end of the base unit, as it appears in FIGURE 5, it will be noted that corresponding parts, or individual holes of the double holes, are spaced longitudinally a distance x . This same relationship exists between the centers of corresponding individual holes of double holes that are aligned transversely going across the base unit. Thus, the four holes in the left end have corresponding individual holes, the centers of which are spaced apart a distance x such that their centers are at the four corners of a square. This same relationship exists between corresponding individual holes of the four double holes that are disposed in the right end as the base unit appears in FIGURE 5. Thus, considering the four holes that exist in the left part of FIGURE 5, and considering the corresponding parts of each one of these holes, there is a hole existing at each corner of two squares that might be said to overlap in the sense that one is shifted with respect to the other longitudinally of the base unit by an amount equal to the distance y . The same relationship exists in the pattern of double holes shown at the right in FIGURE 5. A slightly different relationship exists between those individual parts of the double holes that are closest to the center of the base unit, as it appears in FIGURE 5. In this instance, the individual holes of each of the four double holes that are farthest from the center of the unit are spaced apart a distance x so that the four sets of double holes near the mid portion of the unit are closer together than those two sets of four that are in the opposite ends. Otherwise expressed, a member having plugs thereon that might engage in corresponding individual holes in the pattern of four at the left would engage in opposing holes in the pattern of four that is in the mid portion of the base unit.

The above relationship of individual holes of the various double holes that are utilized in the base unit is an important one in the fabrication of the various toys that can be made using the components of the kit of this invention.

Further, FIGURE 5 shows the underside of the base unit, and as shown, there are three recesses in two areas of the base unit extending transversely of the unit. Considering those that are in the right hand portion of the base unit as it appears in FIGURE 5, there are two transversely arranged, generally rectangular recesses 15—15 that are in those areas of the base unit between the respec-

tive longitudinally disposed wooden dowels 11—11 and the outer side edges of the base unit. There is, in addition, a shorter longitudinally disposed central recess 16. In the preferred embodiment, these notches are slightly tapered going inwardly and they do not extend more than one-half of the way through the unit going face to face. The same pattern of recesses is repeated in the other endwise portion of the base unit, these recesses being designated 17—17 for the ones that are in the areas outside of the two wooden dowels 11—11 and designated 18 at the middle.

The next major component of the kit comprises two seat units, designated generally by the numeral 19. Each one of these seat units comprises a bottom panel 20, a back panel 21 and two side panels 22—22. Preferably, each seat unit is molded of foamed polystyrene. It is preferred that the back 21 of each one of the seat units be straight up and down and that the forward edges of the two side walls 22—22 be straight up and down. However, as shown, the two side walls 22—22 may flare outwardly. An important consideration is the plugs 23—23 and the circular, tapered recesses 24—24 that are on the bottom of each one of these seat units. (See FIGURE 9.) Considering a square traced on the bottom panel 20 of each seat unit, the two plugs 23—23 are located at diametrically opposed corners of the square, whereas, the two recesses 24—24 are located at the other two corners of this square. The sides of this square are the dimension x , equal to the dimensions x of FIGURE 5 for the base unit 10. Each plug 23—23 is of a size, being tapered, to fit into an individual hole 13 of any one of the double holes 12. Furthermore, each one of the two circular recesses 24—24 is of a size to receive a tapered plug 23. Thus, as best illustrated in FIGURES 4 and 12, two of the individual components 19 may be placed bottom panel 20 to bottom panel 20 with the plugs 23—23 of one unit engaged in the circular, tapered recesses 24—24 of the other, and thus, form an "easy chair." Equally important, because of the relationship of the various dimensions x , the seat units may be used singly or in twos to form various toys when one or both of the seat units are placed on the base unit.

As shown in FIGURE 1, two seat units are in place upon the base unit. In each instance, the backs 21 of the two units are pointed in the same direction with the plugs 23—23 of the respective units being located in those individual holes of the set of four at the left that are toward the left as appears in FIGURE 5 and with the plugs 23—23 of the second seat unit being placed in those individual holes of the set of four toward the right that are toward the right. In this way, the two seat units are spaced apart as shown in FIGURE 1. The same individual holes of the two sets of four each may be utilized to receive the plugs 23—23 of two seat units that are placed with the back of one at one side of the base unit and the back of the other at the opposite side of the base unit as appears in FIGURE 3 to form a love seat. As shown in FIGURE 3, two such seat units are mounted in the individual holes of the double holes that are closer to the center of the base unit and in this way, a doll's cradle may be formed and as will be explained, it is preferred that rocker components of the kit be used in this toy. It is also preferred that the rocker components be used in the love seat as shown in FIGURE 2.

Referring now to FIGURE 6, a combined rocker and axle journal is shown at 25. This unit has two rectangular lugs 26—26 at the upper side thereof that are of a size and shape to be received in the two recesses 15—15, or those designated 17—17, that are formed in the bottom side of the base unit 10. There is, in addition, a center lug 27 that is adapted to be received in the recess 16 or the recess 18. It is preferred that two such combined rocker and axle journal units 25 be provided with the kit. Unit 25 is preferably formed so that its lower surface is

on an arc 28, as shown in FIGURE 6, so that when placed on the bottom of the base unit it forms a rocker as shown in FIGURES 2 and 3. Additionally, the underside of the unit 25 has a slot 29 therein that is designed to receive a cylindrical wooden dowel 30, the dowel forming an axle. Dowel 30, as shown in FIGURE 7, has annular grooves at 31—31 at its outer ends, these grooves being designed to receive snap-on washers 32—32 that hold wheels 33, such as that shown in FIGURE 8, to the axle. As in the case of the other major components, the combined rocker and axle journal devices 25 and the wheels 33 are formed of molded, foamed polystyrene. It is preferred that each one of the wheels 33 have a relatively substantially wide tread 34 and a hub 35 with a central hole 36 of a size to receive either one of the opposite ends of the wooden dowel 30. It is also preferred that the slot 29 on the underside of the combined rocker and axle mount be of the size to receive the wooden dowel in close friction fit so that no fasteners are necessary in attaching the axle to unit 25. The fit between the bore 36 and the wooden dowel 30 is such that the wheel 33 may turn freely on axle 30.

The toy cannon shown in FIGURES 1, 13 and 14 is not a part of this invention, and thus, it is believed that the illustrations sufficiently disclose this part of the toy and that additional descriptive matter is not necessary.

Having described my invention, I claim:

1. A kit by which a child may fabricate different types of playthings comprising a rectangular base unit of molded foamed polystyrene, said base unit being approximately two and one-half times as long as it is wide, a pair of wooden dowels embedded in said base unit paralleling the longitudinal center line thereof on opposite sides of said center line to strengthen said base unit, there being eight identical double holes through said base arranged in two identical sets of four double holes each, the individual holes of each double hole being identical and tapering inwardly from the opposite faces of said base unit such that the smallest diameter of each hole is midway between said faces, the centers of the holes of each double hole being spaced apart a distance in the direction longitudinally of said base unit approximately equal to three fourths of the diameter of an individual hole at a face of said base unit, the centers of corresponding individual holes of the four double holes of each of said sets defining a square at each end of said base with the opposite sides of each square paralleling the opposite side edges of said base unit, those four double holes including two from each of the different sets of four that are closer to the center of said base unit having the individual holes therein that are farther from said center of said base unit disposed with their centers defining a square equal in size to the previously mentioned squares, two seat units, each seat unit of molded foamed polystyrene comprising a bottom, a back and two sides, the bottom of each unit having two identical plugs projecting therefrom and two identical sockets therein of a size to receive a plug, the centers of said sockets and plugs being disposed to define a square equal in size to the previously mentioned squares with the plugs at diagonally opposite corners and the sockets being diagonally opposed at the other two corners of said square, and said plugs being of a size to fit individual holes of said double holes in said base unit, whereby said seat units may be disposed with their bottoms on said base unit with their backs at opposite sides thereof, at the same side thereof, facing one another, opposite one another and by utilizing different individual holes of said sets of double holes, the seat units may be together at the center of the base unit or separated at said center.
2. A kit as in claim 1 in which two rockers of molded foamed polystyrene are provided, and means are provided at the underside of said base unit to receive said rockers so that they extend transversely of said base unit in spaced parallel relation.

3. A kit as in claim 2 in which two sets of two molded foamed polystyrene wheels and axles therefor are provided, and said rockers adapted to receive said axles.

4. A kit by which a child may fabricate different types of playthings comprising a rectangular base unit of molded foamed polystyrene, there being eight identical double holes through said base arranged in two identical sets of four double holes each, the individual holes of each double hole being identical and tapering inwardly from the opposite faces of said base unit such that the smallest diameter of each hole is midway between said faces, the center lines of the holes of each double hole being spaced apart a distance in the direction longitudinally of said base unit approximately equal to three fourths of the diameter of an individual hole at a face of said base unit, the centers of corresponding individual holes of the four double holes of each of said sets defining a square at each end of said base with the opposite sides of each square paralleling the opposite side edges of said base unit, those four double holes including two from each of the different sets of four that are the ones closer to the

center of said base unit having the individual holes therein that are farther from said center of said base unit disposed with their centers defining a square equal in size to the previously mentioned squares, two seat units, each 5 seat unit comprising a bottom, a back and two sides, the bottom of each unit having two identical plugs projecting therefrom and two identical sockets therein of a size to receive a plug, the centers of said sockets and plugs being disposed on a square equal in size to the previously mentioned square with the plugs at diagonally opposite corners and the sockets being diagonally opposed at the other two corners of said square, and said plugs being of a size to fit individual holes of said double holes.
